(57) **CLAIM**

I claim the ornamental design for a high torque surgical needle hub, substantially as shown and described.

DESCRIPTION

FIG. 1 is a side view of a surgical needle hub of a surgical needle of the present invention;

FIG. 2 is a side perspective view thereof;

FIG. 3 is a front perspective view thereof;

FIG. 4 is a front-side perspective view thereof; and,

FIG. 5 is a back-side perspective view thereof.

FIGS. 1-5 show features of a surgical needle with broken lines. These features are for illustrating reference of environmental structure only and do not form any part of the claimed design.
